UNITED STATES PATENT OFFICE.

FRANK W. WARDWELL, OF CAMBRIDGE, AND CHARLES E. LETTENMAYER,
OF WEST LAMERVILLE, MASSACHUSETTS; SAID LETTENMAYER AS-
SIGNOR TO SAID WARDWELL.

BOOK-COVER PROTECTOR.

SPECIFICATION forming part of Letters Patent No. 234,096, dated November 2, 1880.

Application filed August 31, 1880. (Model.)

To all whom it may concern:

Be it known that we, FRANK WELLINGTON WARDWELL, of Cambridge, in the county of Middlesex and State of Massachusetts, and CHARLES ERFORD LETTENMAYER, of West Lamerville, in the county and State aforesaid, have invented a new and Improved Book-Covering, of which the following is a specification.

10 The object of our invention is to provide a new and improved book-covering which is simple in construction and effective in use.

In the accompanying drawings, Figure 1 is an inside view of our improved book-covering, 15 showing the same opened. Fig. 2 is a cross-sectional elevation of the same, showing the same closed and surrounding a book. Fig. 3 is a side view of the same, showing a larger book placed into it.

20 Similar letters of reference indicate corresponding parts.

The two stiff sides A A of the covering are each bent over on the inner side at the outer edge to form pockets B B to receive the outer 25 ends of the book-covers C C. The sides of the pockets B B are only attached to the covers A A at the outer edges and at the bottom D, whereas they are not attached at E, so as to permit books that are larger than the cov- 30 ering to be placed into the same, as shown in Fig. 3.

The stiff sides are connected by a pliable back, F, which can be folded in case thin books are to be covered, as shown in Fig. 2.

35 A strap, string, or band, H, which may be of elastic material, cloth, or leather, as may be desired, is passed through the aperture G in

one of the sides A, passes across the back F on the outside, then up on the inside of the other side A, then passes over the back F 40 again, passes through the upper aperture G in the side A, and the two ends are then united, either by means of a buckle, J, or by knotting the band.

The book-covering is used as follows: The 45 book-covering is adjusted according to the thickness of the book by means of the band or strap H, for by decreasing the length of the same the back F is folded, so as to adapt the covering for a thinner book. The ends of the 50 book-covers C C are then placed into the pockets B B of the covering, which is held to the book thereby. If the book is longer than the covering, it will project beyond the same, as shown, and for this reason the upper ends of 55 the pockets are not attached to the sides A A.

The straps may be attached to the sides A A at the inner edges, and may pass around the back of the covering only, and may also be provided with buckles for adjusting them, 60 if desired.

Having thus described our invention, what we claim as new, and desire to secure by Letters Patent, is—

A covering for books consisting of two stiff 65 sides, A A, connected by a pliable back, F, the said sides A A being bent to form the pockets B B and provided with the band H, applied as shown and described.

FRANK W. WARDWELL.
CHARLES E. LETTENMAYER.
